UNITED STATES PATENT OFFICE.

DORIS M. EATON, OF SPRINGFIELD, MASSACHUSETTS.

DESIGN FOR AN ASH TRAY OR SIMILAR ARTICLE.

Application filed January 18, 1928. Serial No. 24,911. Term of patent 7 years.

To all whom it may concern:

Be it known that I, DORIS M. EATON, a citizen of the United States, residing at Springfield, in the county of Hampden and State of Massachusetts, have invented a new, original, and ornamental Design for an Ash Tray or Similar Article, of which the following is a specification, reference being had to the accompanying drawings, forming part thereof.

Fig. 1 is a front elevational view.
Fig. 2 is a side elevational view; and
Fig. 3 is a plan view partially in section on the line 3—3 of Fig. 2 showing my new design for an ash tray, or similar article.

I claim:
The ornamental design for an ash tray or similar article, as shown.

DORIS M. EATON.
